UNITED STATES PATENT OFFICE.

LOUIS C. WAGNER, OF NEW YORK, N. Y.

DESIGN FOR A CIGAR-BAND.

SPECIFICATION forming part of Design No. 25,983, dated September 8, 1896.

Application filed June 24, 1896. Serial No. 596,805. Term of patent 7 years.

To all whom it may concern:

Be it known that I, LOUIS C. WAGNER, a citizen of the United States, residing at New York, in the county and State of New York, have invented and produced a new and original Design for Cigar-Bands, of which the following is a specification, reference being had to the accompanying drawing, forming a part thereof.

- 10 The leading feature of the design consists in a cigar-band having an enlarged central portion with outwardly-curved edges and tapering end portions or wings, the edges of said wings being formed with fanciful curves,
- 15 said band containing an approximately central crown and arabesque or similar ornaments on its end portions.

In the drawing, A represents the enlarged central portion of the band, and B B' the end portions or wings. The central portion A is curved outwardly at the top and bottom edges, and the end portions B B' taper and are formed in fanciful curves at their edges, the end portion B further having a plain oblong 25 extension or tab b. The central portion A

contains a substantially central crown a, from which radiate a number of lines forming a glory a', while below and partially surrounding these ornaments is a scroll a² for containing a suitable inscription. Each end portion 30 or wing B B' contains, near the end of the scroll a², a medallion C, while geometrically-arranged arabesque or similar ornaments D are arranged beyond the medallions. The described ornamentations are surrounded by 35 fanciful curves and scrolls forming an ornamental border E, which is separated from the edges of the band by a plain margin e. The band is embossed and brilliantly colored.

What I claim is—

The design for a cigar-band substantially as described and shown.

In testimony that I claim the foregoing as my invention I have signed my name in presence of two subscribing witnesses.

LOUIS C. WAGNER.
